Primary Examiner — Derrick Holland*Assistant Examiner* — Jennifer O King(74) *Attorney, Agent, or Firm* — Law Offices of Michael L. Wise, LLC(57) **CLAIM**

The ornamental design for an electrical outlet cover, as shown and described.

DESCRIPTION

FIG. 1 is a front perspective view of an electrical outlet cover showing my new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is a rear elevation view thereof shown in environmental use.

The broken lines shown represent unclaimed subject matter and form no part of the claimed design.
